UNITED STATES PATENT OFFICE.

HIRAM PHILLIPS, OF ST. LOUIS, MISSOURI.

PLUMBING ATTACHMENT.

957,709.

Specification of Letters Patent. Patented May 10, 1910.

Application filed April 8, 1909. Serial No. 488,580.

To all whom it may concern:

Be it known that I, HIRAM PHILLIPS, a citizen of the United States, residing at the city of St. Louis, State of Missouri, have invented certain new and useful Improvements in Plumbing Attachments, of which the following is a specification, reference being had therein to the accompanying drawings.

10 This invention consists in the location and arrangement of disinfectant holders in connection with plumbing.

In the drawings, like numbers of reference denote like parts wherever they occur, and 15 Figure 1 is an elevation showing the location of the disinfectant holder relative to the other parts of the plumbing; Fig. 2 is a sectional view, on an enlarged scale, showing the arrangement of the disinfectant holder within the pipe and the position of same relative to the opening through which it is to be filled; Figs. 3 and 4 illustrate modified forms of receptacles; and Fig. 5 shows a different, but analogous, mode of 20 holding the disinfectant in the desired location.

As will be readily understood, and as is common, the flushing water runs from tank 1 to bowl 2 through pipe 3. By means of 30 suitable joints or unions 4, pipe section 5 is inserted between the upper and the lower part of pipe 3, and the flushing water is obliged to pass through said section 5. A basket 6, having openings therein or being 35 formed of reticulated material, as shown in the drawings, is located in said section 5 and preferably adjacent to the opening 7 normally closed by threaded plug 8.

The disinfectant, preferably in the shape 40 of balls 9, is placed in the basket 6, and when the flushing water descends through pipe 3 it is obliged to flow through the basket 6, which is located directly in its path of travel, and thus over and through 45 the disinfectant 9, moistening and removing some particles therefrom and carrying the disinfecting effect to the desired points.

It should be understood that the shape of 50 the basket or disinfectant holder proper is immaterial, as it may be of either the three forms depicted in the drawings, or it may be simply a flat perforated plate extending across the section 5 of pipe 3, and may be supported therein by any desired means.

55 For instance, in the drawings a bilge 10 is imbedded to section 5, and the upper rim 11

of basket 6 rests within said bilge and upon the corner 12 leading to opening 7. Such mode of support is equally available for the forms of basket shown in Figs. 3 and 4 and for a perforated flat plate instead of the flat wire netting shown in Fig. 4. Other means of support for the basket or equivalent receptacles may, if desired, be employed, such, for instance, as lugs, a flange, or notches within the pipe and projections from the basket seating therein. The various forms of support are not illustrated in the drawings, as there are too many optional forms.

Fig. 3 illustrates a continuous pipe 3 instead of a pair of pipes 3, a gooseneck 13 being formed therein. Said gooseneck is given such shape as to form a chamber or receptacle or holder 14 for the disinfectant 9, same being inserted therein through opening 15 normally closed by plug or cap 16. A plug 17 controls an aperture that gives access to chamber 14, and can be removed for the purpose of cleaning chamber 14, or any other necessary purpose. When the water descends through pipe 3, it passes through chamber 14 and, therefore, over and past the disinfectant 9, which, for this form of device, might be made heavier than in the other forms herein illustrated and described, so as to be prevented from floating away in the water, or the same purpose may be accomplished by the provision of a screen 18 at the top of the gooseneck, or elsewhere, so as not to prevent the insertion of disinfectant 9 into chamber 14 through opening 15 and preferably, also, so as to throw same back into said chamber if same momentarily floats out of chamber 14.

It will be observed that three important advantages are obtained by the use of this invention. In the first place, unsightly attachments to plumbing are done away with. In the second place, waste due to constant dripping is eliminated, and the utmost economy is effected because of the disinfectant being located in a sealed pipe (sealed at the top by the water in tank 1 and at the bottom by the water in most forms of receptacle 2), whereby evaporation of the disinfectant is prevented. In the third place, many people find the odor arising from disinfectant holders exterior to the flushing pipe very disagreeable, which objection is entirely obviated by the present invention, inasmuch as there could be no escape of

odor out of either receptacle 2 or tank 1, because of both ends of pipe 3 being water sealed. Even in the forms of bowl 2 where no such water-seal exists, there would be no escape of disinfectant odors, because same would rise upwardly from the disinfectant in greater degree than they would descend, and would be prevented by the water from escaping from tank 1.

10 Many minor changes in the form, location, and arrangement of the several parts may be made without departing from the nature and spirit of this invention.

I claim:

11 1. The combination of a reservoir, a receptacle spaced from the reservoir, a pair of pipes connected by a hollow removable member, one of said pipes being connected to said reservoir and the other being connected to said receptacle, said member having a bilge and an out-turned mouth, and a disinfectant receptacle having openings therein and supported conjointly by said bilge and said out-turned mouth.

25 2. In combination with a reservoir and a receptacle, a pipe connected to the reservoir and a second pipe connected to the receptacle, a hollow removable member having

its ends connected to the inner ends of the pipes and having a central bilge and an outwardly extending mouth which is located at one side of the bilge, the lower end of said bilge and said mouth being in alignment to form supporting ledges, a disinfectant receptacle having a flared open upper end which seats on said supporting ledges, and a closure for the mouth.

3. The combination with a tank and a receptacle, of a pair of pipes one connected to the tank and the other to the receptacle, said pipes having their inner ends arranged in spaced relation, a removable member disposed in said space and having its ends secured to said inner ends of the pipe, an out-turned mouth formed on said member, and a removable disinfectant receptacle arranged within said member, having means at its upper end to engage said member for supporting the disinfectant receptacle.

In testimony whereof I have affixed my signature in presence of two witnesses.

HIRAM PHILLIPS.
